UNITED STATES PATENT OFFICE.

DAVID B. JAMES, OF SAN FRANCISCO, CALIFORNIA, ASSIGNOR TO FRANK A. HUNTINGTON, OF SAME PLACE.

MINER'S CANDLESTICK.

SPECIFICATION forming part of Letters Patent No. 366,320, dated July 12, 1887.

Application filed August 30, 1886. Serial No. 212,365. (No model.)

To all whom it may concern.

Be it known that I, DAVID B. JAMES, of the city and county of San Francisco, State of California, have invented an Improvement in 5 Miners' Candlesticks; and I hereby declare the following to be a full, clear, and exact description of the same.

My invention relates to a novel candlestick for miners' use.

10 It consists in the devices which I shall hereinafter fully describe and claim.

Referring to the accompanying drawing for a more complete explanation of my invention, the figure is a perspective view of my device, 15 showing the manner of holding the candle in place.

The coil A is formed of one or more turns of wire, and is made of sufficient diameter to allow a candle to be placed in it loosely. From 20 the upper side of the coil the wire is carried upward and curved, as shown, so as to form a pointed hook, B, which may be hung upon a projection of rock within the mine or upon other points where it is desired to support the 25 candle. From the lower end of the coil the wire extends backward, and another coil of one or more turns is formed at C, from which the wire is again carried forward beneath and beyond the first coil, A, as shown at D. The 30 elasticity of the second coil forces the arm D beneath the first coil, A, when there is no candle within it, but when the candle has been placed within this coil, so that its lower end projects just beneath the coil the arm D will 35 press against the side of the candle, and will thus hold it firmly within the coil, and prevent its slipping out. When the candle is burned down very short, the arm D may be allowed to pass beneath the coil and the bottom of the 40 candle will rest upon this arm, the candle being held upright by the turns of the coil until it is all burned out. The arm D has its end pointed, so that it may be thrust into a timber or into a crevice in the rock. The coil C

serves as a handle by which to press it in if it 45 is desired to hold the candle in this manner, instead of by means of the hook B, before described. The weight of the parts which project upon each side of the candle-holding coil 50 A is such that when hung loosely by the hook B the candle will remain in a nearly or quite upright position, and by this construction either the hook or the point D may be employed to suspend the candlestick, according to convenience.

I am aware a miner's candlestick has been constructed of a single piece of metal, having a coil or return bend, which forms a handle, said candlestick being also provided with a socket within which the candle is held, and a 55 pointed end. Such construction I therefore do not broadly claim as my invention, wherein the candlestick is composed of a single wire bent to form two coils, and having a pointed hook at one end by which the device may be hung 60 upon a projection of rock, and a pointed arm adapted to be thrust into a timber or into a crevice in the rock.

Having thus described my invention, what I claim as new, and desire to secure by Letters 70 Patent, is—

1. An improved candlestick composed of a continuous piece of wire having the two coils A and C and a spring arm, D, extending from the coil C, bearing against the side of the candle beneath the coil A, and having its end pointed, substantially as herein described.

2. The candle-holding coil A, the coil C, and elastic arm D, projecting beyond and beneath the coil A, in combination with the hook-extension B, substantially as herein described.

In witness whereof I have hereunto set my hand.

DAVID B. JAMES.
